UNITED STATES PATENT OFFICE.

JAMES E. GREENSMITH, OF BROOKLINE, MASSACHUSETTS, ASSIGNOR, BY DIRECT AND MESNE ASSIGNMENTS, TO BOSTON SCALE & MACHINE COMPANY, OF BOSTON, MASSACHUSETTS, A CORPORATION OF MASSACHUSETTS.

HYDRAULIC GRINDER.

Application filed April 19, 1920. Serial No. 374,815.

This invention relates to grinding or abrading machines, and with regard to certain more specific features thereof to fluid-pressure-operated grinding or abrading machines.

5 The invention has for one of its objects the provision of a reliably effective fluid-pressure feed for the operating tool of a machine of the character above mentioned, and more particularly the invention contemplates the idea of 10 hydraulic means for steadily and continuously reciprocating a ram or slide which carries the active tool of the machine, without noticeable shock or vibration. Other objects of the invention are to provide reliably operative 15 means to easily control the speed and range of movement of the tool-carrier, to effect automatically a rectilinear reciprocatory movement of said tool-carrier without impairing the action of the hydraulic system, and where- 20 by the feed of the work table of the machine is placed under the control of the feeding means for the tool-carrier, so that the work table or its carrier may be fed automatically at predetermined intervals and the time and 25 extent of feed of the work table may be governed primarily by the same means as governs the movement of the tool-carrier.

It is another object of the invention to provide simple and reliably operative means for 30 rotating the grinding tool and the work table, in combination with the means, above mentioned, whereby the reciprocatory feed of the tool-carrier and the feed of the work table toward the tool are effected by the fluid pressure means.

35 It will be apparent, therefore, that the general objects of the invention are to improve a grinding or abrading machine by generally simplifying the construction thereof, by designing the parts and units for quick, convenient and accurate assembly, by introducing a feed for the grinding tool, which permits of a maximum range of speeds, substantially any feed desired being obtainable, and the feed 40 being of a steady and uniform character in either direction of reciprocatory movement, and by rendering a grinding machine automatically operative to a high degree.

45 Other objects will be in part obvious, and in part pointed out particularly hereinafter.

The invention, accordingly, consists in the various features of construction, combination of elements and arrangements of parts, which

will be exemplified by the construction hereinafter set forth and the scope of the application of which will be indicated by the following claims.

In the drawings, wherein is represented one of various possible embodiments of the invention:

55 Fig. 1 is a view, in front elevation, of the improved grinding machine.

60 Fig. 2 is a view of a portion of Fig. 1 enlarged and sectioned to show more clearly the interior construction of the tool-carrier and its fluid-pressure feed.

65 Fig. 3 is a left-end elevational view of Fig. 1.

70 Fig. 4 is a sectional view taken on the line 4—4 of Fig. 1.

75 Fig. 5 is a view in section taken on the line 5—5 of Fig. 1, looking in the direction of the arrows.

Fig. 6 is a sectional view of the tool-carrier slide taken on line 6—6 of Fig. 2.

80 Fig. 7 is a view in section taken on a line 7—7 of Fig. 4. This view shows the universal or flexible coupling between the change speed gearing and the spindle of the work holding table.

85 Fig. 8 is a view in section taken on a line 8—8 of Fig. 4 showing the devices whereby the work table may be given a slight range of pivotal adjustment.

Fig. 9 is a sectional view of the reversing valve and its operating mechanism.

90 Fig. 10 is a view in front elevation of a portion of the reversing valve mechanism.

Figs. 11 and 12 are fragmentary views relating to the reversing valve mechanism.

95 Figs. 13 and 14 are views of the change speed unit showing clearly the different gear changes which may be effected, and also showing the means by which the unit may be attached to, or detached from, the body of the machine.

Fig. 15 is an enlargement of a portion of Fig. 1, relating to the means for feeding the work table against the tool.

100 Fig. 16 is of the mechanism shown in Fig. 15 as viewed from the right-end of the machine.

105 Fig. 17 is a view in section taken on the line 17—17 of Fig. 15 looking in the direction of the arrows.

Fig. 18 is a diagrammatic view of the hy-

draulic system and Fig. 19 is a diagrammatic view of the reversing valve in said system.

Referring now more particularly to the drawings wherein similar reference characters refer to similar parts throughout the several views, it will be noted that in the present embodiment a base or machine bed A has mounted thereon, at the top, a tool-carrying slide B. At the left of the base (see Fig. 1) there is mounted a second slide or carrier C adapted to be moved relatively to the base and in a direction substantially at a right angle to the movement of the tool-carrier. The machine has a main driving shaft D journaled in bearings in the end walls of the base, and in Fig. 1 of the drawings a clutch E is illustrated which is adapted for actuation by a foot treadle F in order to connect and disconnect, at the will of the operator, the main driving pulley G with the main drive shaft. From a pulley H on the shaft D is driven the pump which circulates the lubricating or cooling medium. From a sprocket I, fixed to the shaft D there is driven the primary shaft J of the change speed transmission mechanism between the main drive shaft and the work spindle. To the right of the sprocket I, as viewed in Fig. 1, there is a sprocket K from which the pump L of the hydraulic system is driven. To the left of sprocket I is a pulley M, fixed to the drive shaft and from which the operating-tool spindle is rotated during the reciprocation of the tool-carrying slide. Within the hollow bed or base or frame of the machine there is located an oil-reservoir N from which is drawn and returned the fluid which is used for reciprocating the tool-carrying slide and effecting the automatic feed of the work table. This reservoir is arranged preferably at the lower part of the machine and is connected by suitable piping to the pump L then through a valve mechanism O to an operating piston and cylinder mechanism P. The tool-carrying slide B is connected to a projecting stem of the piston. A change speed transmission unit Q is fitted into the frame of the machine through an aperture at the front thereof and is adapted for ready attachment or detachment from the machine frame and the remainder of the transmission. A work carrier R comprises the slide C and a spindle carrying rocker S, there being provision for pivotal adjustment of the latter with respect to the slide.

The tool actuating mechanism.

In the present embodiment of the invention the tool is adapted to rotate at a relatively high speed while simultaneously traversing the work. To these ends (see Figs. 1 and 2) the pulley M is connected by belt 20 to an elongated pulley 21. The latter is fixed to a spindle 22 journaled at opposite ends in trunnions or bearings 23 and 24 provided in

the main tool-carrier casting B. The belt 20 is held taut and restricted against longitudinal movement with the tool-carrier by means of a spring pressed idler pulley 25 (Fig. 3) so that the spindle of the carrier slide in its longitudinal reciprocation slides under the belt but is nevertheless rotated thereby.

At the end of the spindle 22 a grinding or abrading tool 26 is suitably fixed and this tool is preferably of circular or discular configuration. The tool is suitably housed as indicated at 27 and one bearing of the tool spindle is provided with devices for taking up any looseness in the bearings.

The top of the machine frame A is provided with a dove-tail way 28 within which is slidably fitted the dove-tail base 30 of the tool-carrier. To this base is bolted a depending ear 31 through which is projected an extremity 32 of the stem 33 of a piston 34, which latter is a part of the fluid pressure operated apparatus of the machine. For giving the tool-carrier its reciprocatory movement a cylinder 35, within which the piston is fitted, is provided with ports 36 and 37 respectively at either end of the cylinder. To cause movement of the tool-carrier or ram in a forward direction fluid is supplied under pressure through the port 36 and is simultaneously exhausted through the port 37 at the opposite end of the cylinder. To reverse the direction of movement of the carrier the direction of flow of the fluid is reversed. This reversal is accomplished automatically or may be manually if desired through the agency of the valve mechanism O and its actuating means (see Figs. 1, 2, 9, 10, 11, and 12). The extremity 32 of the piston stem 33 is threaded where it projects through the ear 31. Nuts 38 are provided on the extremity at either side of the ear and permit of securing the ram or slide in different adjusted positions with respect to the cylinder. In this way provision is made for varying the position of the working stroke of the tool.

The valve mechanism O comprises a housing consisting of a short cylindrical tube 40 having a flange or annular lip 41 by which it is secured in an opening provided in front of the frame A, a rear closure plate 42 and a front closure member 43. Within the body of the housing there is fitted a cage 44 and within this is rotatively fitted a valve 45. The body of the valve 45 is in the form of a shell having two substantially diagrammatically opposed ports 46 and 47 of long and narrow configuration. The exterior of the body portion of the valve is cleared away intermediate two narrow end bands 48 and 49, as indicated in Fig. 11 at 50, except for small areas bordering the ports before mentioned, an area 51 which co-operates with a port 52 communicating with the exhaust, and an area 53 substantially at the top of the valve which is left for the purpose of obtaining a high degree

of valve balance. The valve cage 44 has two ports 54 and 55 corresponding in size and shape with ports 46 and 47 of the valve and the said valve ports are adapted respectively 5 and alternately to register with ports 54 and 55 of the cage. The valve as shown in Figs. 2 and 12 is in a neutral position shutting off entirely the fluid from the forward and rearward supply pipes of the cylinder and from 10 an exhaust pipe 60. Should the valve be turned to cause registration of the ports 46 and 54 the fluid will pass through the interior of the hollow shell of the valve then outwardly through port 46 of the valve plug, port 54 15 of the valve cage, forward cylinder supply pipe 61 to the forward end of the cylinder, whereupon the piston 34 will be urged rearwardly and the tool-carrier in the same direction. It will be noted that when these 20 two ports are in communication, the port 47 of the valve is moved out of registration with the port 55 of the valve cage which is in communication with a rearward cylinder supply pipe 62. The raised area surrounding the 25 port 47 is moved beyond the port 55 of the cage so that fluid in the cylinder to the rear of the piston is permitted to exhaust through the rearward cylinder pipe 62 through the port 55, around the exterior of the valve, passing 30 by the raised areas at the ends thereof, and discharging through the port 52 of the valve cage into the exhaust pipe 60.

The direction of flow of the liquid may be 35 reversed by a movement of the valve to cause registration of the ports 47 and 55 which will cause a relationship of the opposite ports 46 and 54 similar to the one permitting the exhaust just described. This improved valve construction provides a nicety of balance of 40 the valve parts. The fluid pressure is distributed inside and outside of the valve. The fluid used having a lubricating characteristic, and flowing about between the plug and the cage, causes constant lubrication. The 45 routing of the exterior of the valve leaving only the few raised areas necessary to close, open or partition the ports, reduces friction to a minimum and the valve is set in its different operative positions by a movement 50 through a very slight angular range. The balance and consequent ease of operation obtained by this valve structure has an important bearing on the adaptability of the machine for work of extreme precision. Inasmuch as the tool carrier is automatic in 55 its reciprocatory feeding movement, and the reversal of its movement at each extreme is under its own control through the medium of the valve, it is highly advantageous to reduce the burden of the valve operation to the 60 lowest possible point. In so doing there is maintained in the hydraulic system a uniformity of pressure which obviates surging and uneven feeding.

65 The fluid is supplied from the pump L

through an inlet pipe 65 threaded into the rear closure plate 42 of the valve. From an inspection of Fig. 9 of the drawings it will be apparent that the fluid is discharged therefrom into the interior of the valve 45. Passing through the registered ports it finds its way to one end or the other of the cylinder according to which ports are in registration and the fluid at the opposite end of the cylinder respectively is exhausted through another 70 portion of the valve and exhaust pipe 60. It is only when the valve is moved to register one pair of ports as an inlet to one end of the cylinder that the exhaust passage through the valve is opened, therefore the liquid in 80 the exhaust end of the cylinder is confined therein except when the fluid is being supplied under pressure to the other end of the cylinder. In the exhaust pipe 60 there is provided a manually operable valve 70 for 85 regulating the rate of flow of the fluid through the exhaust and which consequently regulates the rate of movement of the piston in the cylinder 35. The exhaust pipe 60 discharges into the container N as shown clearly 90 in Figs. 1 and 18 of the drawings. An end thrust bearing 71 is provided between the valve and the front closure member of the valve housing, and a conduit 72 is formed in the forward end of the valve which permits a 95 portion of the operating fluid to flow into a chamber 73 surrounding said bearing and maintain it constantly lubricated. It will be apparent from Fig. 9 of the drawings that there is a slight space at the rear of the valve 100 between it and the rear closure plate 42. There is therefore a distribution of the fluid pressure at both ends as well as within and around the valve. The cylinder 35 is provided at either end near the top with relatively small air vents 74 and 75 which communicate with the oil container N by means of pipes 76 and 77, each of which is provided with a pet cock as shown at 78 in Fig. 18. The hydraulic system is also provided 105 with a by-pass 80 extending from the intake pipe to the exhaust pipe. This by-pass is normally closed to the intake pipe by a spring pressed relief valve 81 which may be regulated to permit part of the fluid to flow from 110 the intake directly into the exhaust should the pump pressure be too high for conditions in the reversing valve, cylinder or other parts of the system.

120 The reversing valve operating mechanism.

The valve 45 has a forwardly extending stem 85 which has a bearing in the front closure plate of the valve housing. Suitable packing is provided to prevent leakage of oil 125 and the same is held in place by a hollow screw member 86 tapped into the forward part of the front closure plate and being itself bored to serve as a part or continuation of the bearing for the valve. The forward 130

part of the front closure member 43 of the valve mechanism is formed in the shape of a short cylindrical boss, and mounted on this boss for free rotative movement but held 5 against longitudinal displacement is a plate 87 having a central recession 88 from its upper edge, providing a yoke. The plate 87 also carries two links 90 and 91 pivotally supported forwardly thereof as shown 10 clearly in Fig. 10. These links have their free ends equipped with cam rollers 92 and 93 which are constrained to movement toward one another by means of a spring 94 connected at either end to pins 95 and 96 15 projecting respectively from the rear wall of each link. An operating lever 100 is pivotally mounted on the frame of the machine, the pivot being preferably near the top or the slide way for the tool carriage. The 20 lever 100 has a short upward extension beyond its pivot providing a handle 101 by which it may be operated, and also, journalled in the rear of said upward extension is a roller 102 adapted to be abutted by actuating members or stops 103 and 104 which are 25 adjustably fixed on the tool carrier. The lever 100 has at its lower free extremity 105 a roller 106 positioned within the recession 88 of the plate 87 and adapted to bear against 30 one or the other of the side walls of the yoke accordingly as the lever is pivotally moving in one direction or the other. At the forward extremity of the stem of the valve 45 there is fixed a cam member 110 having a 35 depending arm 111. The said arm is formed with stop faces 112 and 113 adapted to abut adjustable stops 114 and 115 provided on the front of the valve housing and consequently in fixed relation with the frame of the 40 machine. The cam member is so shaped as to urge the rollers 92 and 93 of the links of the plate 87 away from each other as the operating handle is moved from one extreme position toward the other. This movement of 45 the links extends the spring 94 and when the handle has reached the point predetermined as its opposite extremity of movement points 116 and 117 of the cam member pass by the rollers 92 and 93 respectively and the spring 50 94 causes the rollers to become effective on the opposite faces of the cam to cause that member to move quickly to its opposite extremity of movement. The cam member being as before stated fixed to the stem of the valve 45 55 carries the valve through a range of angular movement which breaks communication between one set of ports and effects registration of the other set of ports. The arm 111 of the cam member has at its lower end a spring 60 detent 120 which during the automatic operation of the machine is locked inoperative by the tongue and groove device indicated at 121 but which may be utilized to lock the valve in any one of the three desired positions. 65 The actuating blocks 103 and 104, by which

the handle is automatically operated, are applied to the tool carrying slide by means of T-bolt locking devices, the heads of which are slidably adjustable in a T slot 122 extending longitudinally of the tool carrying 70 slide. By this construction the actuating blocks may be quickly and conveniently moved to and locked in any desired position. The bodies of the actuating blocks are pivotally mounted so that if it is desired they may 75 be swung about their pivots to a position where they will not be intercepted by the roller 102 of the operating lever 100 during the movement of the tool carrier. For limiting the extent of movement of the yoke member 87 there are provided on the flange 41 of the valve housing 40 adjustable stops 130 and 131. By adjustment of the set screws of these stops accurate registration of the valve 80 ports may be obtained. 85

Means are provided by which the tool-carrying slide may be longitudinally reciprocated by hand. To this end (see Fig. 6) a stub shaft 132 is projected through the frame of the machine journalled in a boss 133. 90 This shaft carries at its outer end a hand wheel 134 and at its inner end a pinion 135 both of which are fixed on the shaft. A rack 136 is secured to the under side of the tool-carrying slide and has teeth meshing with 95 the teeth of the pinion. If desired the shaft 132 may be made shiftable axially so that the pinion may be withdrawn from mesh with rack 136.

The work actuating mechanism.

100

By the structure of the embodiment of the invention herein shown the work may be rotated while being acted upon by the edge of the rotary grinding tool. There is also provision for advancing the work toward the tool at predetermined times. This advance or feed of the work may be manually, or automatically under control of the movement of the tool-carrying slide.

105

As previously stated the main drive shaft is connected through chain and sprockets to a shaft J of the change speed transmission unit Q. This unit is shown clearly in Figs. 1, 13 and 14, and comprises a box or frame 115 140 having an arcuate front wall 141 connectible to the frame by an attaching flange 142.

110

In assembling the machine the transmission box is passed rearwardly through an 120 aperture 143 in the front wall of the machine frame and secured to said frame by bolts passing through the attaching flange 142 into the frame. The machine frame comprises two cross struts 145 and 146 and at the 125 rear of the transmission box means are provided as indicated at 147 and 148 for attaching same to the struts. Journalled in side walls 150 and 151 of the transmission box there are three shafts J, 152 and 153; the 130

shaft J being the primary shaft which is connected to the main drive shaft. Pivotedly mounted on this shaft is a rocker arm 154 which carries, loosely mounted thereon, a gear 155 above its pivot point and a gear 156 below its pivot point. The rocker arm 154 extends forwardly in the transmission box and has an extension in the nature of a short shaft 157 which projects through a slot 158 in the arcuate front wall of the box. Fixed to this short shaft extension outside of the transmission box is a combined handle and detent member 160, by which the rocker arm may be manipulated to cause engagement or dis-engagement of the gears 155 and 156 with gears fixed on the intermediate shaft 152 as will more clearly appear hereinafter. The rocker arm 154 may be locked in any desired position by a spring pressed detent pin 161 which is adapted to engage with recesses 162 properly spaced on the front wall of the transmission box in line with the movement of the detent pin.

A drive sprocket 170 is fixed to the primary shaft J of the transmission. There is also fixed on this shaft two gears 171 and 172, the first adjacent the sprocket 170, and the second being of larger diameter and adjacent the side wall 150 of the box. In permanent mesh with the small diameter gear 171 is the gear 156 which is carried by the rocker arm 154 below its pivot, and in permanent mesh with the larger diameter gear 172 is the gear 155 which is carried by the rocker arm 155 above its pivot. On the intermediate shaft there is fixed a single member on which are cut two gears 180 and 181 and also fixed upon the intermediate shaft, adjacent to the side wall of the box, is a gear 182. The gear 180 is of comparatively large diameter, the gear 182 somewhat smaller and the gear 181 comparatively small in diameter. As shown in Fig. 13, when the rocker arm 154 is in its lower position with respect to the slot in the front of the transmission box the transmission is completed to the intermediate shaft from the large diameter gear 172 on the primary shaft, through the gear 155 carried by the rocker arm above its pivot, to the gear 182 of intermediate diameter on the intermediate shaft. If the rocker arm is moved to its upper position this transmission is broken and another is established from the small diameter gear 171 on the primary shaft through the gear 156 carried by the rocker arm below its pivot, to the gear 180 of comparative large diameter on the intermediate shaft. By this gearing the intermediate shaft may be given either one of two speeds.

On the shaft 153 there is splined a sleeve 190, exteriorly of which there is loosely pivotedly mounted a second rocker arm 191. This rocker arm carries above its pivot, loosely journalled, a gear 192, and below its

pivot, loosely journalled, it carries a gear 193 of smaller diameter. Fixed to, or a part of the sleeve 190 there are two gears, one 194, of small diameter on one side of the rocker arm and which is in permanent mesh with the large gear 192 carried by the rocker arm, and the other 195 of larger diameter which is in permanent mesh with the smaller gear 193 carried by the rocker arm below its pivot point. This second rocker arm is also provided with a shaft extension projecting through the front wall of the transmission box and the shaft extension has a combined handle and detent device attached to it corresponding to the one attached to the rocker arm 154. Reference to Fig. 1 of the drawings will show clearly the character of the opening through the front wall of the transmission box. It will be noted that there is a main horizontal artery and four parallel slots 200, 201, 202 and 203 extending at right angles from said artery; two of these slots extend upwardly and two downwardly. It is possible, therefore, to move the rocker arm 191 and its sleeve 190 along the shaft 153 in order to establish connection between the gears 192 and 193, carried by the rocker arm, and either of the gears 180 or 181 of the intermediate shaft. The large gear 192 may thus be meshed with the large gear 180 of the intermediate shaft in which case the rocker arm shaft extension will obtain a position at the top of slot 203. If desired the sleeve may be shifted axially to mesh the large gear 192 with the small gear 181 of the intermediate shaft. The shaft extension of the rocker arm will at that time be at the top of slot 202. And so with the gear 193, carried by the rocker arm 191 below its pivot, which may be meshed with either of the gears 180 or 181 of the intermediate shaft. This provides for four different speeds of the shaft 153 from a single speed of the intermediate shaft. It will be noted, however, that there is provision for two speeds of the intermediate shaft, and that therefore by the gearing described eight different speeds of the shaft 153 may be obtained. The latter shaft is connected by an easily separable and flexible joint 205, a splined sleeve and shaft 206 and a second flexible joint 207 to an operating shaft 208 for the work table spindle (see Fig. 7). The frame of the machine and the work-carrier slide are apertured as indicated at 210 permitting the transmission to extend through to the operating shaft which is journalled in an adjustable rocker casting 211 which latter is pivotally supported between parallel webs 212 and 213 projecting from the work-carrier slide C.

The work table spindle is indicated at 220. It has a frustro-conical upper bearing which seats in a bearing block 221 inserted and fixed in the top of the rocker casting 211. At its lower extremity the spindle has a bearing in

- a split bushing 222, the exterior of which is tapered slightly from the top to the bottom and this bushing is seated within a sleeve 223 having its interior of corresponding taper.
- 5 The sleeve is fixed within an aperture provided for it in the lower part of the rocker casting and is held in fixed position by bolts 224 which pass through a flange 225 of the sleeve and also secure to the flange of the, 10 sleeve an annular member 226 having an interiorly projecting lip 227 which in turn confines against vertical movement an interiorly threaded adjusting nut 228 while at the same time permitting rotative movement of said 15 nut. The taper of the split bushing 228 continues for a considerable part of the length of said bushing and is then supplemented by a threaded portion of uniform diameter. It is with this threaded portion that the nut 228 co- 20 operates so that rotation of the nut, confined as it is against vertical movement, will impart a vertical movement to the bushing. This will move the bushing in or out of the interiorly tapered sleeve and will accordingly constrict or enlarge the diameter of the bearing. 25 By this construction the spindle bearing may be adjusted to the degree desired. The lower extremity of the spindle is threaded and equipped with suitable lock nuts and washer.
- 30 About midway of the spindle a collar 230 is pinned, above which there is loosely mounted a worm wheel 231 adapted to mesh with a worm 232 of the spindle operating shaft 208. The upper surface of this worm wheel is pro- 35 vided with clutch teeth 233 adapted to co-operate with clutch teeth 234 of a vertically shiftable clutch 235 splined on the operating spindle. This clutch is adapted for manual operation by means of a yoke 236 pivotally 40 mounted on an ear 237 extending inwardly from the side wall of the rocker casting. The yoke is fixed on a short rocker shaft 238 which projects outwardly through the rocker casting as shown clearly in Fig. 1 and to which 45 is fixed an operating lever and handle 240. The handle has a detent characteristic similar to others hereinbefore described and the locking pin thereof co-operates with recesses in the rocker casting whereby the clutch may be 50 locked in or out of operative position. A work table 241 of any suitable form or character may be attached to the upper end of the work spindle 220.

For various reasons it is desired that the 55 work table have a capability of a small range of adjustment to and from a horizontal plane. In the present embodiment the rocker casting having a pivotal mounting at the top of the carrier-slide has a connection at either side, 60 near the bottom of the casting, of a T-bolt and cross slot type. The slots are indicated at 242 and 243 and the T-bolt heads at 244 and 245. A tightening up on the nuts 246 will secure the rocker in position and the adjustment is effected by an adjusting bolt 247 swiv-

elly mounted in the rocker casting and threaded into a block 248 swivelly mounted in the web 213 of the work-carrier slide. A vernier 250 is provided on the rocker casting which co-operates with an index number fixed to the 70 slide, whereby the extent of adjustment can be determined.

As heretofore stated the work-carrier slide has a dove-tail connection with the frame of the machine whereby the entire 75 work-carrier may have a vertical up or down movement. At the work table end of the frame there is a standard 251 which, suitably journals a screw threaded rotatable shaft 252. At the top of this shaft 80 there is a beveled gear 253 which meshes with a beveled pinion 254 on the end of a shaft 255 which is horizontally disposed and journalled in a suitable boss 256 provided on the web 213 of the work-carrier slide. 85 This shaft 255 has fixed on its forward end a hand wheel 257 the rotation of which will cause rotation of the shaft. This effects a vertical movement of the slide due to the latter's connection with the screw threaded shaft 90 252 by means of an interiorly threaded boss 258 projecting from the slide and through which the screw shaft is threaded.

The present invention contemplates the placing of the feed of the work table under 95 the control of the action of the tool-carrier slide, by means reliably operative, simple, inexpensive, and which make for quiet and non-vibratory operation of the machine. To this end a pair of cam members 260 and 261 are 100 adjustably fixed in spaced relation on the tool-carrier slide. Through a system of links and levers which will be later described in detail a ratchet wheel 262 loosely mounted on a stub shaft 263, carried by the slide C, is intermittently actuated. The ratchet wheel is keyed to the hub 264 of a gear 265 which is rotative on the stub shaft 263. An arm 266 is loosely mounted on the hub 264 of the gear 265 intermediate the ratchet and the said 110 gear. This arm carries a spring pressed pawl 267 adapted to mesh with the teeth of the ratchet wheel 262. The free end of the arm 266 is connected by means of a link 268 to one arm 269 of a bell crank lever 270. The latter is pivotally mounted on the frame at 271 and is normally urged in a direction tending to retract the pawl, by means of a spring 272 one end of which is connected with a short arm 273 of the lever and the other end of which is connected to a pin 274 extending from the frame. The short arm 273 of the bell-crank lever is forked at its free end as indicated at 275 to straddle a connecting link 276, and is connected to said link by a pin 277. 115 This link carries at its upper free end a roller 278, and intermediate the ends of the link the same has a connection to an arm 280 pivoted to the frame of the machine at 281. An adjustable stop 290 is provided on the frame 120 125 130

of the machine adapted to limit the movement of the bell-crank lever under the influence of its spring, and thereby limit the retrograde movement of the pawl. The spaced cam members 260 and 261 have opposed inclined cam faces 292 and horizontal dwells 293. As the tool-carrier slide moves under the influence of the fluid pressure and from right to left across and beyond the work 10 the roller 278 will be acted upon by the inclined surface of the cam member 261 and urged downwardly in a substantially vertical direction. The arm 280 will swing on its pivot and the bell-crank lever will swing 15 about its axis against the action of the spring 272. The pawl 267 being at this time in engagement with the ratchet wheel will rotate the latter a few degrees and as the tool-carrier slide continues through its active range of 20 movement the roller 278 will contact with the horizontal dwell 293 of the cam member. This accomplishes a step of upward feed of the work-carrying slide inasmuch as the gear 265, which rotates with the ratchet wheel, 25 meshes with a gear 291 which is fixed on the shaft 255. Said shaft carries the beveled pinion which meshes with the beveled gear at the top of the elevating screw shaft 252. As the tool-carrier slide is reversed through the 30 action of the automatic valve and starts on its movement from left to right, the dwell 293 of the cam member 261 passes beyond the cam roller 278 and the spring 272 is permitted to urge the bell-crank lever in a direction to retract the pawl for a subsequent step of feed. 35 This subsequent step takes place as the tool completes its grinding operation for that direction of movement, and is effected by contact of the inclined surface 292 of the other cam member with the cam roller 278. It will be noted that in the present embodiment a step of feed is imparted to the work table at the end of a movement of the tool-carrier slide in either direction of reciprocation. 40 There is therefore the condition of a step of feed of the work table taking place just prior to the grinding or abrading tool beginning its action upon the work. The tool traverses the work at any feed of speed desired, this 45 rate of speed being controllable by the operator by manipulation of the valve 70. The speed of movement of the tool-carrier slide has a maximum range and uniformity due to the fluid pressure actuating means and the 50 control therefor, and it is possible to impart to and maintain a feed to the tool-carrier slide which is almost imperceptible should this be desired. The reversal of the tool carrying slide may be automatically effected 55 by the mechanism described and may be caused to take place at the point desired by adjustment of the stops 103 and 104. The cams of the work-carrier slide feeding means are preferably adjusted in accordance with 60 the positions of the said stops so that the step 65

feed of the work table becomes effective just after the tool leaves the surface which it is grinding and before the return of the tool to active grinding position in the opposite direction of movement. It will be noted that 70 the tool spindle and the work spindle are rotated through mechanical agencies while the feeding movement of both the tool carrier and the work table are effected under the control of the hydraulic system. 75

Should it be desired to discontinue the feed of the work table at some predetermined point this may be effected by means of a shield 300 arranged at the end of an arm 301 which latter is adapted to be secured in any 80 desired position of adjustment to a hub 302 extending rearwardly from the ratchet wheel 262 so that whatever position the shield is secured in it will rotate jointly with the ratchet wheel and at a predetermined point will intercept the pawl 267 and subsequent reciprocations of the pawl will be ineffective to rotate the wheel. 85

Operation and assembly. 90

The work table is preferably a magnetic chuck to which current may be supplied through a switch mounted on the work spindle rocker, but not shown in the drawings. The work being positioned on the table an electric circuit is closed through the coils of the chuck by manual operation of the switch heretofore referred to, and with a suitable grinding or abrading tool in position on the end of the tool carrying spindle the machine 95 is started in operation by movement of the foot treadle F which causes engagement of the members of the clutch E. From the main drive shaft the tool spindle is rotated at a constant speed and the work spindle is rotated at the desired speed through having previously set the transmission mechanism to engage the gears of the proper train. The 100 automatic feed for the work table may be in or out of operation as desired accordingly as the shield 300 is or is not in position to prevent engagement of the pawl 267 with the teeth of the ratchet wheel. If desired the transmission may be broken by swinging the 105 pawl about its pivot irrespective of the position of the shield. Assuming the automatic feed of the work table to be out of operation the tool carrier slide will be reciprocated horizontally to cause the tool to traverse the rotating work piece. At the end of each movement in one direction the work 110 table may be given a step feed by manual operation of the hand wheel 257. At the point in the operation which is predetermined as the end of the movement of the tool carrier in one direction, one of the operating members or stops carried by the slide picks up the operating handle of the reversing valve 115 and carries it beyond the center; the valve mechanism itself completing its throw to reg- 120 125 130

ister the opposite ports of the valve. The speed of reciprocatory movement of the tool-carrying slide is controlled by the hand operable valve 70 arranged in the exhaust pipe 5 of the hydraulic system. By means of this valve the back pressure of the escaping fluid of the cylinder 35 may be increased or diminished to secure any desired steady speed of the tool-carrying slide within an exceedingly 10 wide range.

With the pawl 267 adjusted for engagement with the teeth of the ratchet wheel, the link and lever mechanism heretofore described becomes effective as an automatically 15 operative feed for the work table which feed is under the control of the movement of the tool carrying slide. It is understood that fluid pressure means have been extensively employed in grinding machines but partic- 20 ularly for the purpose of feeding the work carrier. The present machine employs a fluid pressure device for effecting a reciprocatory movement of the grinding wheel carrier and by the present arrangement the feed 25 of the grinding wheel has a wide speed range in both directions of movement and is particularly steady and effective. The reversing mechanism is highly automatic and quite 30 easy of operation due to the balanced character of the reversing valve which makes fur- 35 ther for a steady operation of the entire machine inasmuch as the resistance which it offers to the tool carrying slide in its recipro- cation is reduced to a minimum. No sub-stantial additional burden is put upon the hydraulic system.

The change speed gears, being assembled in a unitary structure, may be quickly and conveniently removed from the machine by 40 disconnecting the bolts which hold the transmission box to the frame; separating the universal joint 205 and removing the entire transmission box from the machine. Both spindles of the machine have one bearing 45 which is constructed to provide for obtaining the proper adjustment and to compensate for wear. As the means for securing the tool and work table to their respective spindles forms no part of the present invention 50 a description of this means is not included herein.

As many changes might be made in the above construction and as many apparently 55 widely different embodiments of the invention might be made without departing from the scope thereof, it is intended that all matter contained in the foregoing description or shown in the accompanying drawings shall be interpreted as illustrative and not in a 60 limiting sense.

What I claim is:

1. In a machine of the character described, in combination, a tool, hydraulically actuated means for reciprocating the tool across work, 65 a work support, means for rotating said

work support, means under control of the tool actuating means for feeding the work toward the tool at the end of the movement of the tool in either direction of its reciprocating travel, means for rotating the tool 70 as it traverses the work, and a valve under control of the tool actuating means for automatically effecting the reversal of movement of said tool.

2. In a machine of the character described, 75 in combination, a tool, hydraulically actuated means for reciprocating the tool across work, a work support, means for rotating said work support, means under control of the tool actuating means for feeding the 80 work toward the tool at the end of the movement of the tool in either direction of its reciprocating travel, means for rotating the tool as it traverses the work, a hydraulic power system, and a valve in the exhaust 85 thereof to vary the speed of the reciprocatory movement of said tool.

3. In a machine of the character described, 90 in combination, a tool, hydraulically actuated means for reciprocating the tool across work, a work support, means for rotating said work support, means under control of the tool actuating means for feeding the work toward the tool at the end of the movement of the tool in either direction of its reciprocating 95 travel, a valve under control of the tool actuating means for automatically effecting the reversal of movement of said tool, a hydraulic power system, and a valve in the exhaust thereof to vary the speed of the re- 100 ciprocatory movement of said tool.

4. In a machine of the character described, in combination, a tool carriage adapted to support a rotary abrading tool, and means for continuously reciprocating the tool carriage 105 and causing a cutting action of the tool on work in both directions of reciprocation, comprising hydraulic carriage-actuating means, devices for automatically effecting reversal of movement of said carriage at the end of its 110 working stroke in either direction, and mechanism for causing uniform rotation of said tool as the carriage reciprocates.

5. In a machine of the character described, 115 in combination, a tool carriage adapted to support a rotary abrading tool, means for continuously reciprocating the tool carriage and causing cutting action of the tool on work in both directions of reciprocation, comprising hydraulic carriage-actuating 120 means and devices for automatically effecting reversal of movement of said carriage at the end of its working stroke in either direction, a work support, means for rotating said work support, and means under control of the carriage actuating means for feeding the work 125 toward the tool at intervals.

6. In a machine of the character described, 130 in combination, a tool carriage adapted to support a rotary abrading tool, means for con-

tinuously reciprocating the tool carriage and causing a cutting action of the tool on work in both directions of reciprocation, comprising hydraulic carriage-actuating means, devices for automatically effecting reversal of movement of said carriage at the end of its working stroke in either direction, and mechanism for causing uniform rotation of said tool as the carriage reciprocates, a work support, means for rotating said work support, and means under control of the carriage actuating means for feeding the work toward the tool at intervals.

7. In a machine of the character described, in combination, a work carrier, a tool, means for causing simultaneous and continuous rotary and reciprocating movements of the tool, said means comprising a rectilinearly reciprocating tool carriage and hydraulic actuating devices for effecting a working stroke of the tool in both directions of reciprocation, means for rotating said work carrier, and means under control of the carriage actuating means for feeding the work toward the tool at intervals.

8. In a machine of the character described, in combination, a work carrier, a tool, means for causing simultaneous and continuous rotary and reciprocating movements of the tool, said means comprising a rectilinearly reciprocating tool carriage, hydraulic actuating devices for effecting a working stroke of the tool in both directions of reciprocation, devices adapted to rotate the tool uniformly as to speed and direction while the tool carriage is moving throughout its range of reciprocating travel, means for rotating said work carrier, and means under control of the carriage actuating means for feeding the work toward the tool at intervals.

9. In a machine of the character described, in combination, a carriage slidably arranged on a support and provided with a tool spindle and an abrading tool on said spindle, a hydraulic actuating means for said carriage, a manually operated means associated with said hydraulic system whereby the fluid flow may be varied in any amount so that the feed of the carriage can be varied to any extent between maximum and minimum limits, spaced dogs on the carriage operating on a quick action valve control means, a valve for reversing the direction of fluid flow to obtain a reverse movement of the carriage at the same speed of feed, and means for rotating the tool spindle at a uniform speed during the movement of the carriage in both directions.

10. In a machine of the character described, in combination, fluid pressure means, a movable carriage, a tool mounted on said carriage, means adapted to cause rotation of said tool to produce an abrading action on work, a work support and means for rotating the same, connections arranged between the

work support and the carriage and between the carriage and said fluid pressure means whereby the feed of both the carriage and the work support is derived from said fluid pressure means, and a reversing mechanism adapted to operate as the carriage moves in either direction to cause reversal of the carriage movement and a feed of the work support in a constant direction.

11. In a machine of the character described, in combination, a self contained hydraulic power system comprising a pump, a system of piping, a cylinder and a piston; a tool carriage connected to said piston, a tool mounted on said carriage, means for rotating said tool in a constant direction, a work support, means for feeding the work support toward said tool, a reversing valve in said power system adapted to be operated by said carriage in either direction of movement to change the direction of fluid flow in said cylinder, and means for controlling the rate of fluid flow in the exhaust side of said system and holding it uniform irrespective of the direction of flow in said cylinder.

12. In a machine of the character described, in combination, a hydraulic power system, a main driving shaft, a tool carriage adapted to be continuously reciprocated in said hydraulic system, a grinding tool mechanically driven from said driving shaft while the carriage is reciprocated, means for causing a reversal of fluid flow in a portion of said hydraulic system at a predetermined point in the carriage movement and a consequent reverse movement of the carriage and tool while the tool is continued mechanically driven in a constant direction.

13. In a machine of the character described, in combination, a hydraulic power system, a main driving shaft, a tool carriage adapted to be continuously reciprocated in said hydraulic system, a grinding tool mechanically driven from said driving shaft while the carriage is reciprocated, means for causing a reversal of fluid flow in a portion of said hydraulic system at a predetermined point in the carriage movement and a consequent reverse movement of the carriage and tool while the tool is continued mechanically driven in a constant direction, a work holder rotated from said driving shaft, and means actuated by the hydraulic means adapted to effect intermittent and unidirectional feeding movement of said work holder.

14. In a machine of the character described, in combination, a slidable carriage, a rotatable tool mounted thereon, a hydraulic power system for moving said carriage, a reversing valve in the hydraulic system whereby the fluid flow is reversed in a part thereof to cause reversal of the carriage movement, controlling means for the fluid flow whereby the speed of carriage movement may be varied, means on the carriage adapted to operate said

reversing valve in both directions of carriage movement thereby causing continuous reciprocation of the carriage and means for rotating said tool continuously in the same direction and at a constant speed while the carriage is continuously reciprocated, the said controlling means for the fluid flow being capable of operation during the reciprocating movement of the carriage and providing complete selectivity of any desired feeding speed between maximum and minimum limits.

15. In a machine of the character described, in combination, fluid pressure means, a tool carriage slidably mounted and adapted for continuous reciprocatory movement by said fluid pressure means, a tool arranged on said carriage, means independent of said fluid pressure means adapted to continuously rotate said tool and cause it to operate on work in either direction of movement of said carriage, a work support, a member actuated by said carriage and connections from said member to said work support, a reversing valve in the fluid pressure means, and actuating members on said carriage for both the reversing valve and the connections to the work support whereby the feed of the carriage and the feed of the work support are effected from the fluid pressure means, the feed of the carriage being in opposite directions on each actuation and the feed of the work support being in a constant direction.

16. In a machine of the character described, in combination, a tool spindle and a work spindle arranged in intersecting planes, a carriage for the tool spindle, a hydraulic power system, mechanical agencies for rotating both spindle, and control devices in the hydraulic power system whereby a continuous reciprocatory movement of the carriage is effected and a feeding movement of the work spindle is effected.

17. In a machine of the character described, in combination, a carriage movable back and forth having a tool carrying spindle journaled therein, mechanical agencies for continuously rotating the spindle while it is moved axially with the carriage, fluid pressure means and connections therefrom to said carriage, reversing means in said fluid pressure means to cause the directional change of movement of said carriage, a speed control for the carriage comprising means adapted to

maintain a solid body of fluid opposed to the movement of said carriage and the fluid pressure causing same.

18. In a machine of the character described, in combination, a hydraulic power system, a reciprocating carriage having a grinding tool spindle and rotary grinding tool thereon, said carriage having its feeding movement from said hydraulic system, another motor means for rotating the tool spindle, a quick-action reversing valve in the hydraulic system adapted to be acted upon by the carriage to stop and reverse the carriage feeding movement independently of the spindle rotating means, whereby the tool is continued in unidirectional rotation irrespective of a change in feeding direction of the carriage.

19. In a machine of the character described, in combination, a hydraulic power system, a reciprocating carriage having a grinding tool spindle and rotary grinding tool thereon, said carriage having its feeding movement from said hydraulic system, another motor means for rotating the tool spindle, a quick-action reversing valve in the hydraulic system adapted to be acted upon by the carriage to stop and reverse the carriage feeding movement independently of the spindle rotating means, whereby the tool is continued in unidirectional rotation irrespective of a change in feeding direction of the carriage, and throttle means in the hydraulic system whereby the speed of carriage feed may be varied.

20. In a machine of the character described, in combination, a rotary abrading tool rotatably mounted on a slide carriage, means for rotating said tool, fluid motor devices comprising a source of fluid supply under pressure, a cylinder, a piston in said cylinder, connections between said piston and said slide carriage, pipes connecting said source of fluid supply with opposite ends of said cylinder, a quick action valve in the piping whereby the fluid is directed to one or the other of the cylinder ends; a work holder rotatable substantially at a right angle to said tool, means adapted to be actuated to incrementally feed the work holder, and means on said carriage co-acting with said valve and said work holder feeding means adapted to actuate both at predetermined times.

JAMES E. GREENSMITH.
